UNITED STATES PATENT OFFICE

JOSEPH C. HOUCK, OF LOS ANGELES, CALIFORNIA

ADVERTISING DEVICE

Application filed May 26, 1932. Serial No. 613,717.

This invention relates to improvements in an advertising device of that type in which a series of display cards are hinged at an edge to a carrier rotatably mounted in a casing 5 provided with a display opening, a motor being provided for rotating the carrier so that the cards are successively displayed through the opening in the casing. Such devices are placed in store windows and other places for 10 public observation, such as passenger vehicles. When mounted in motor busses, economy of space in the installation and operating of the device is a main requirement. To meet this requirement, the size of the equipment is cur- 15 tailed to such an extent that the simultaneous display of two cards is necessary to provide sufficient space for a single advertisement. As the carrier is rotated, two cards, in edge- 20 to-edge relation and with complementary advertising matter displayed thereon, are momentarily positioned in the display opening of the casing.

In previous devices of this type, to accommodate as many cards as possible, the cards 25 are hinged closely together in the carrier; as the carrier is rotated, the cards rub together and soon wear out, requiring frequent replacement.

One of the objects of the instant invention 30 is to provide means for preventing the rubbing together of the cards and thereby avoiding the wear and tear that would result from the cards rubbing together. In one way this is accomplished by mounting each card in 35 the face of a metallic frame and hinging the frame in the carrier so that the metallic backs of the frames are held in sliding contact while the faces of the frames holding the cards are held apart so that the cards 40 cannot rub together. The means for carrying out this and other objects is described in detail hereinafter, pointed out in the appended claims and illustrated by the accompany- 45 ing drawings.

In the accompanying drawings, in which similar reference characters designate corresponding parts,

Figure 1 is a longitudinal vertical section of an advertising device embodying the invention, the display cards being omitted.

Figure 2 is an end view of the casing, showing in section the gearing for rotating the card-carrier.

Figure 3 is a front elevation of the device with the display cards partly broken away. 55

Figure 4 is an end elevation, partly broken away, showing the motor and its connection for driving the card-carrier.

Figure 5 is an enlarged detail sectional view, showing the gearing for transmitting 60 the drive of the motor to the shaft of the card-carrier.

Figure 6 is a similar view at right-angles to that shown in Fig. 5.

Figure 7 is an enlarged detail sectional 65 view, showing the slip-clutch connecting the gear driven by the motor with the end of the shaft carrying the card-carrier.

Figure 8 is an enlarged sectional view of the slip-clutch. 70

Figure 9 is an end view of the same.

Figure 10 is an enlarged detail view showing one of the hubs in which is journaled 75 an end of the shaft of the card-carrier.

Figure 11 is an enlarged detail view, partly 75 in section and broken away in parts, showing the mounting of the card-frames in the carrier.

Figure 12 is an enlarged detail view, showing the link connection between one of the 80 rods to which the card-frame is hinged and the supporting ring.

Figure 13 is a detail view showing the clutch member attached to the shaft for rotating the carrier shaft. 85

Figure 14 is a detail view, showing a part of one of the casing heads and the guide-way for the transparent cover for closing the display opening of the casing.

Referring to the drawings in detail, more 90 particularly to Figs. 1-4, 11 designates the casing in which are mounted the carrier for the display cards and the mechanism for rotating the carrier. This casing is generally semi-cylindrical with its ends closed by the 95 sides or heads 12 secured in the cylindrical ends. Legs 13 are provided for supporting the casing on a plane surface, as in a store window. For mounting the casing in the forward part of a bus, suitable brackets (not 100

shown) may be provided for the purpose. In the front of the casing is an opening 14 (Fig. 3) for the display of the advertising cards carried by the carrier mounted therein. Extending along the casing at the lower edge of the display is the elongated hood 15 formed in the cylindrical wall of the container. In this hood are mounted electric light bulbs 16 (Fig. 4) to illuminate the cards appearing at the display opening.

Slidable over the display opening is a cover or shield 17 of transparent flexible material, such as celophane. This shield fits between the sides 12 of the casing and its side edges travel in grooves 18 formed between the cylindrical wall of the casing and the angle strips 19 secured to the sides 12. The lower part of the shield is clamped between the bars 20, the ends of which slide in the opposite grooves 18. The lower edge part 21 of the shield extends below the bars and is bent inward so that it projects above the hood 15 when the shield is closed, as shown in Fig. 4. When the shield is closed, entrance of dust to the casing and tampering with the cards is prevented.

Mounted in the axial center of the casing 11 is the tubular shaft 22 supporting the card carrier. This shaft is journaled in the bearing hubs 23, (Fig. 10) secured to the inner faces of the casing heads 12, which are outwardly dished, as at 24, to house the hubs. Means, hereinafter described, is provided for rotating the shaft in the bearing hubs. In the inner face of each of the hubs 23 is a groove 25 (Figs. 10-11) approximately concentric with the axis of the shaft 22. Adjacent the front edge of each hub, as at 26, the groove is widened and flares outwardly to communicate with the horizontal slot 27 leading through the front part of the hub. Extending between the two hubs are the wire rods 28 with their ends slidable in the opposite grooves 25. These rods are placed in the grooves by passing their ends through the horizontal slots 27 leading into the grooves. Displaceable cotter pins 29 passing through the front parts of the hubs prevent the escape of the rods through the slots 27 during the operation of the machine.

The rods 28 are held in parallel spaced relation to each other and to the shaft 22 by the rotatable followers 30 (Figs. 1 and 11) coacting with the grooves 25 guiding the ends of the rods. These followers are circular and are concentrically fixed on the opposite ends of the shaft 22 adjacent to the hubs 23. Each follower has at its circumferential part a series of radial spokes 31 interspersed with a series of slots 32 of uniform length and depth. The spokes extend across the groove 25 at any part of the latter and the ends of the rods 28 riding in the slots 32 are held in spaced relation as they travel around the groove during the rotation of the follower turned by

the shaft 22. When the rods reach the flared part 26 of the groove they have considerable play therein, to facilitate their withdrawal through the slot 27 when the cotter pin 29 is withdrawn from the hub. At the extremity of each of the spokes 31 is the beveled spur 33, the purpose of which will be explained later on.

On each of the rods 28 are hinged two frames, 34 and 35, on which are displaceably mounted the display cards. These frames are formed of thin sheet metal, preferably of brass, which will not rust when subjected to moist atmospheric conditions. Circular openings 36 are formed in each frame to lessen its weight. At its outer edge, each frame is folded over, as at 37, to form a strengthening rib and also to form a flange to engage the outer edge of the display card placed on the frame. To the ends of the frame 34 reinforcing strips 38 are welded. Each of the frames is hinged to its respective rod 28 by the lugs 39 projecting from its inner edge and bent over the rod. These lugs form clips to engage the inner edge of the display card mounted on the frame, the outer edge of the card being engaged by the flange 37 at the outer edge of the frame.

As the frames are moved around by the rotation of the followers 30 propelling the rods 28 along the grooves 25, the relative positions of the frames are constantly shifting and this results in a rubbing together of the contacting surfaces. If the display cards carried by the frames and interposed between the same should be subjected to this rubbing action, they would soon be worn out and require replacement. Means are provided to prevent rubbing contact of the cards and at the same time permit a rubbing contact of the frames, which would not injure the cards. This is accomplished by arranging the frames in connected pairs with the members of each pair coupled together with their backs in sliding contact and providing means for holding each pair out of contact with the contiguous pairs. On the outer faces of the members of each pair the display cards are mounted, while the inner faces or backs of the members contact and rub together during the travel of the pair. The cards so carried do not contact with any rubbing part and the sliding contact, between the backs of the frames of each pair, permit the relative shifting of the frames incident to their travel.

Each pair of coupled frames comprises the member 34 hinged to one of the rods 28 and the member 35 hinged to an adjacent rod 28. At each end of the frame 34 a lug 40 projects from the reinforcing strip 38 and is bent over the adjacent end of the frame 35, the two bent over lugs forming hooks coupling the two frames together. The engagement of the hooks with the frame 35 is a loose connection, permitting a relative sliding movement be-

means. The shaft 61 of the motor is connected by the belt 62 with the shaft 63 journaled in the wall of the auxiliary casing 47. On the inner end of the shaft 63 is fixed the 5 worm 64 meshing with the worm-wheel 65 fast on the shaft 66 journaled in the bearing 67 projecting from the inner wall of the auxiliary casing. Fixed on the shaft 66 is the worm 68 meshing with the worm wheel 49, 10 previously described. By means of the intervening gearing the comparatively fast drive of the motor shaft can be stepped down to the slow rotation required of the shaft 22. Most of the gearing is contained in the auxiliary casing, which is closed so that it can be 15 filled with a lubricant.

Preparatory to the operation of the machine, a display card 69 (Fig. 3) is mounted on the outer face of each of the metal frames 20 34 and 35, by shoving one of the longitudinal edges of the card beneath the flange 37 at the outer edge of the frame and the other longitudinal edge beneath the clips formed by lugs 39 at the inner edge. When the 25 motor is set in motion, through the intervening mechanism the shaft 22 is slowly rotated. The followers 30 rotated by the shaft propel the rods 28, to which the frames are hinged, around the orbit defined by the 30 grooves 25 in the opposite hubs 23 (Fig. 11).

As each rod, the rod X for an instance, moves to the extreme forward position in the grooves, the forward frame 34 falls to a pendent position and the frame 35 is held in 35 an upright position, so that momentarily the two frames are held in a vertical plane, so that the advertising cards mounted on their front faces are exposed through the display of the casing, as shown in Fig. 3. As 40 previously described, the frame 34 carried by the rod X is coupled to the frame 35 carried by the preceding rod Z by the hook-lugs 45 40. When the rod X approaches its extreme forward travel in the grooves 25 with both the frames carried by it in an upright position, the preceding rod Z moves downward and to the rear so that the frame 35 carried by it falls and carries with it the frame 34 hinged to the rod X. At the same time the 50 frame 35 carried by the rod X is momentarily held upright by its engagement with the hook-lugs 40 on the frame 34 carried by the succeeding rod Y. In this way the frames of each rod 28 are successively positioned to 55 expose the cards carried by them through the display opening in the front of the casing.

To remove any one of the rods 28, the machine is stopped and the shaft 22 is turned by the crank 70 inserted in the end of the 60 shaft farther from the motor (Figs. 1 and 3), until the rod X, for an instance, is opposite the slots 27 in the hubs 23 (Fig. 11). Then the frames 34 and 35 are respectively released from the frame 35 carried by the rod Z and 65 the frame 34 carried by the rod Y by bending

the hook-lugs 40. The cotter-pins 29 are removed and the rod X is moved through the slots 27 to displace the same and the frames carried by it. The removal of the rod is 70 facilitated by the groove 71 in one of the heads 12 of the casing (Figs. 2 and 4). After the rod is removed the cotter pins are replaced to prevent the other rods from entering the slots.

What I claim is:

1. In a display device, the combination of a casing having a display opening, with a shaft journaled in the casing opposite to the display opening, means for rotating the shaft, hubs secured in the casing having opposite guide-grooves approximately concentric with the shaft, rods extending parallel to the shaft with their ends registering with the guide-grooves, followers fixed on the shaft engaging the rods to hold the latter in spaced relation 80 and to propel the same around the guide-grooves, and card-holding frames hinged on the rods to be displayed in the casing opening as the rods travel around the guide-grooves.

2. In a display device, the combination of a casing having a display opening, with a shaft journaled in the casing opposite to the display opening, means for rotating the shaft, hubs secured in the casing having opposite guide-grooves approximately concentric with the shaft, rods extending parallel to the shaft with their ends registering with the guide-grooves, followers fixed on the shaft having radial slots engaging the rods to hold the latter in spaced relation in the guide grooves, the rotation of the followers by the shaft operating to propel the rods around the guide-grooves, and card-holding frames hinged on the rods to be displayed in the casing opening as the rods travel around the guide-grooves.

3. In a display device, the combination of a casing having a display opening, with a shaft journaled in the casing opposite to the display opening, means for rotating the shaft, hubs secured in the casing having opposite grooves approximately concentric with the shaft, rods extending parallel to the shaft with their ends registering with the guide-grooves, followers fixed on the shaft having radial spokes interspersed with slots engaging the rods to hold the latter in spaced relation, the rotation of the followers by the shaft operating to propel the rods around the guide-grooves, card frames hinged on the rods to be displayed in the casing as the rods travel around the guide-grooves, and lugs on the frames to be engaged by the spokes of the wheels to separate the frames as they travel toward the display opening of the casing.

4. In a display device, the combination of a casing having a display opening, with a shaft journaled in the casing opposite to the display opening, a motor for rotating the shaft, hubs secured in the casing having op-

130

tween the two frames. The coupled frames straddle the space between the two rods to which they are hinged and this connection tends to hold each pair separate from the contiguous pairs. This connection, however, permits relative in and out movement of the two members of each pair as the rods shift in their movement around the grooves 25 in the hubs 23.

10 As the frames 34—35 revolve around the shaft 22, in the direction of the arrow 41 (Fig. 11), they normally tend to hang vertically on the rods 28. If no means was provided to prevent it, in their upward and forward movement the pairs of frames would fall together and clog the operation of the machine. To avoid this, means are provided for lifting the individual pairs of frames as they move upwardly and forwardly in the upper part of 15 the casing. The means employed for this purpose comprises the bevelled spurs 33 on the extremities of the spokes 31 of the followers 30, and the lugs 42 projecting from the reinforcing strips 38 at the opposite ends of 20 the card frames 34. As the card frames revolve around the axis of the machine, as indicated by the arrow 41, Fig. 11, in passing to the rear, as at *a*, the card frames 34—35 hang vertically and there is no tendency of the 25 frames to crowd each other to clog the operation of the machine; but when the frames start to move upwards, as at *b*, they tend to fall together and interfere with the operation of the machine. When the frames start to 30 move upwardly, as at *b*, the spurs 33 of the followers engage the lugs 42 and lift the frames so that they cannot fall together. As the frames move upward and forward they are separated by the continued engagement of 35 the spurs with the lugs.

It is to be observed that only the frames 34 are provided with lugs 42 to engage the spurs 33, and that the frames 35 do not have such lugs. However, each of the frames 35 is coupled to one of the frames 34 by the hook-lugs 40, as previously explained, so that the control of the frame 34 also controls the coupled frame 35. Consequently, each pair of coupled frames 34—35 constitutes a unit and it is 40 the units so constituted that are held in spaced relation in their upward and forward movement to prevent crowding.

Loosely mounted on the shaft 22, at an intermediate part thereof, is the ring 43 (Figs. 55—1, 11 and 12), split transversely at 44 so that the ring can be opened. Loosely carried by the ring is a series of links 45, each of which engages one of the rods 28 at the intermediate point of the latter. The link connection between the rod and ring prevents the rod from bowing, due to the thrust or pull of the frame carried by the rod. Also, as the rod travels around the grooves 25 of the hubs 23, the link connection prevents the ends of the rod 60 from catching in the inner ends of the slots

or passages 27 leading through the front parts of the hubs. The slot 46 in the link, through which passes the ring 43, is of sufficient length to permit the required play of the ends of the rod in the grooves 25, and also to facilitate the detachment of the link from the ring when the rod is removed from the hubs to displace the frames carried by the rod.

Mechanism is provided for slowly rotating the shaft 22 for revolving the frames carrying the display cards. At one end this shaft extends through the intervening head 12 into the auxiliary casing 47, (Figs. 1 and 7), and axially alined with this shaft is the stud-shaft 48 projecting from the opposite wall of the auxiliary casing. On this stud-shaft is journaled the spoked worm-wheel 49. A flexible clutch or coupling is provided for transmitting the drive of the worm-wheel to the shaft 22. This coupling comprises a cylindrical sleeve 50 having a series of recesses 51 (Fig. 8) to engage the spokes of the worm-wheel 49. Within the other end of the sleeve are two spiral springs 52, wound in opposite directions and having frictional contact with the sleeve. These springs are held in place by the lugs 53 projecting inwardly from the wall of the sleeve. The inner ends 54 of the springs are hooked into the ends of the tubular rod 55 extending diametrically across the sleeve. In the coupled relation of the parts, the tubular rod 55 engages the slot 56 (Figs. 8, 9 and 13) extending diametrically across the coupling head 57 fixed on the end of the shaft 22 by the pin 58 passing through the hub of the head and the end of the shaft.

When the worm-wheel 49 is turned to rotate the sleeve 50 in the direction of the arrow 59 (Fig. 9), the sleeve tends to turn the spiral springs with it through the frictional contact. This tendency of the springs to turn with the sleeve is resisted by the engagement of the tubular rod 55 with the coupling head 57; but this resistance causes the tubular rod to expand the springs thereby establishing a non-slipping engagement between the springs and the sleeve so that the drive of the worm-gear is transmitted to rotate the shaft 22. When the machine is at rest, the shaft 22 can be rotated by hand in the same direction, as indicated by the arrow 59 (Fig. 9) by revolving the tubular bar 55 to wind the springs to contract the same and thereby loosen the frictional engagement between the sleeve and the springs. As the sleeve is held stationary by its engagement with the worm-wheel 49, the contracted springs will slip around the sleeve so that the shaft can be turned by the crank 70 displaceable in one end of the shaft.

In the operation of the device, the worm-wheel 49 is driven by the electric motor 60, supplied with current from any suitable source of supply, not shown. The electric motor is of standard make and is mounted on the casing of the machine by any suitable

- posite guide-grooves approximately concentric with the shaft, rods extending parallel to the shaft with their ends registering with the guide-grooves, said hubs having passages leading from the guide-grooves to permit the withdrawal of the rods from the guide grooves, followers fixed on the shaft having radial slots engaging the rods to hold the latter in spaced relation in the guide-grooves, 5 the rotation of the followers by the shaft operating to propel the rods around the guide-grooves, card-holding frames hinged on the rods to be displayed in the casing opening as the rods travel around the guide-grooves, 10 manually operated means for turning the shaft to register a rod with the passages leading from the guide-grooves to permit the withdrawal of the rod and the frames carried by it from the guide-grooves, and displacementable means for closing the passages while the rods are propelled by the followers when the shaft is rotated by the motor. 15
5. In a display device, the combination of a casing having a display opening, with a shaft journaled in the casing, a motor for rotating the shaft, a slip-clutch interposed in the driving connection between the motor and the shaft to permit the rotation of the shaft independently of the motor, hubs secured in 20 the casing having guide grooves approximately concentric with the shaft, rods extending parallel to the shaft with their ends registering with the guide grooves, said hubs having passages leading from the grooves to permit the withdrawal of the rods from the 25 grooves, followers fixed on the shaft having radial slots engaging the rods to hold the latter in spaced relation in the grooves, the rotation of the followers by the shaft operating to 30 propel the rods around the guide grooves, card-holding frames hinged on the rods to be displayed through the casing opening as the rods travel around the guide-grooves, and manually operated means for turning the 35 shaft to register a rod with the passages in the hubs leading from the guide-grooves to permit the withdrawal of the rod from the guide-grooves to displace the frames carried by the rod, said slip-clutch permitting the 40 turning of the shaft independently of the motor. 45
6. In a display device, the combination of a casing having a display opening, with hubs fixed to opposite sides of the casing, a shaft 50 journaled in the hubs, means for rotating the shaft, said hubs having guide-grooves approximately concentric with the shaft, rods extending parallel to the shaft with their ends registering with the guide-grooves, followers 55 fixed on the shaft and engaging the rods to propel said rods around the guide-grooves in spaced relation as the shaft rotates, a pair of frames hinged on each rod to turn by gravity as the frames are carried by the rod past the casing opening, each frame of 60

each pair having a sliding engagement with the opposite frame of the adjacent pair so that the frames of each pair are held apart to prevent rubbing contact of their opposite faces during the travel, and display cards mounted on the opposite frames of each pair to be shown through the casing opening as the frames turn to complementary vertical positions in passing the casing opening. 70

7. In a display device, the combination of a casing having a display opening, with hubs fixed to opposite sides of the casing, a shaft journaled in the hubs, means for rotating the shaft, said hubs having guide-grooves approximately concentric with the shaft, rods 75 extending parallel to the shaft with their ends registering with the guide grooves, followers fixed on the shaft and engaging the rods to propel said rods around the guide-grooves in spaced relation as the shaft rotates, a pair of frames hinged on each rod to turn by gravity as the frames are carried by the rod past the casing opening, hook-lugs 80 on one of the frames of each pair engaging the opposite frame of the adjacent pair to hold the engaged frames in sliding contact and also to hold apart the frames of each pair, and display cards mounted on the opposite frames of each pair to be shown through the casing opening as the frames 85 turn to complementary vertical positions in passing the casing opening. 90

8. In a display device, the combination of a driving shaft, with followers fixed on the ends of the shaft, a series of rods extending 95 parallel with the shaft and engaged at their ends by the followers, a ring loosely encircling the intermediate part of the shaft, and links connecting the individual rods with the ring. 100

In testimony whereof I affix my signature.
JOSEPH C. HOUCK.
